CLAIM

The ornamental design for an occlusive sphygmomanometer for the measuring of arterial blood pressure, substantially as shown.

DESCRIPTION

FIG. 1 is a top perspective view of an occlusive sphygmomanometer for the measuring of arterial blood pressure showing my new design;

FIG. 2 is a bottom plan view thereof;

FIG. 3 is an end view thereof showing the end of the apparatus not visible in FIG. 1; and

FIG. 4 is a side elevation view thereof showing the side not visible in FIG. 1.
